(57) **CLAIM**

We claim the ornamental design for a measuring container, as shown and described.

DESCRIPTION

FIG. 1 is a perspective view of a measuring container according to the new design;

FIG. 2 is a front view of the measuring container shown in FIG. 1, the rear view being a mirror image thereof;

FIG. 3 left side view of the measuring container shown in FIG. 1;

FIG. 4 right side view of the measuring container shown in FIG. 1;

FIG. 5 top view of the measuring container shown in FIG. 1; and,

FIG. 6 is a bottom view of the measuring container shown in FIG. 1.

Features shown in broken lines in the drawings are not part of the claim.

1 Claim, 3 Drawing Sheets
